DESIGN FOR AN ELECTRIC LAMP

Frank Furedy, New York, N. Y., assignor to Twin-Glo Lamp Co. Inc., New York, N. Y., a corporation of New York

Application December 10, 1935, Serial No. 59,993

Term of patent 7 years

To whom it may concern:—

Be it known that I, Frank Furedy, a citizen of the United States residing at New York city, in the county and State of New York, have invented a new, original, and ornamental Design for an Electric Lamp, of which the following is a specification, reference being had to the accompanying drawing, forming a part thereof.

Figure 1 is a perspective view of the electric lamp showing my new design;

Figure 2 is a view in side elevation; and

Figure 3 is a top plan view, thereof.

I claim:

The ornamental design for an electric lamp, substantially as shown.

FRANK FUREDY.
